UNITED STATES PATENT OFFICE.

JAMES H. SLIGH, OF GADSDEN, ALABAMA.

HEADLIGHT FOR LOCOMOTIVES.

SPECIFICATION forming part of Letters Patent No. 613,330, dated November 1, 1898.

Application filed September 20, 1897. Serial No. 652,297. (No model.)

To all whom it may concern:

Be it known that I, JAMES H. SLIGH, a citizen of the United States, residing at Gadsden, in the county of Etowah and State of Alabama, have invented a new and useful Headlight for Locomotives, of which the following is a specification.

The invention relates to improvements in headlights for locomotives.

10 The object of the present invention is to improve the construction of headlights for locomotives and to provide one which will be positively and automatically adjusted to throw the light in the exact direction a locomotive 15 is moving, in order to illuminate the track in front of a train on the sharpest curves as well as along a straight track.

The invention consists in the construction and novel combination and arrangement of 20 parts, as hereinafter fully described, illustrated in the accompanying drawings, and pointed out in the claims hereto appended.

In the drawings, Figure 1 is a perspective view of a portion of a locomotive provided 25 with a headlight constructed in accordance with this invention. Fig. 2 is a transverse sectional view illustrating the manner of mounting the connections between the headlight and the truck on the outside of the front 30 of the boiler or smoke-box. Fig. 3 is a similar view showing the connecting devices extending through the front of the boiler or smoke-box. Fig. 4 is an enlarged detail sectional view illustrating the manner of pivotally mounting the headlight upon a locomotive.

Like numerals of reference designate corresponding parts in the several figures of the drawings.

40 1 designates a locomotive-headlight pivotally mounted upon a locomotive in the usual position at the front thereof upon the top of the boiler or front extension thereof and connected with the same by upper and lower plates 2 and 3, which are centrally perforated 45 for the reception of a pivot-bolt 4. One of the plates is provided with a circular groove 5 and the other has a corresponding tongue 6 fitting in the groove, which forms a way for 50 it, and by this construction the pivoted headlight is rendered perfectly steady.

The headlight is positively connected with

the front truck 7 by a lever 8 and a rock-shaft 9 and is controlled by the pivotal movements of the latter, so that it is automatically and 55 positively turned in the direction the locomotive is traveling. The lever 8, which is disposed substantially vertical, is fulcrumed between its ends at 10, its lower end extending through an opening 11 of the platform or 60 frame of the locomotive and arranged in an eye 12 at one side of the truck, in order to provide a loose connection which will oscillate the lever when the truck turns, but which will prevent the up-and-down movement or 65 vibration of the same from affecting the lever or causing any vibration of the headlight.

The upper end of the lever is connected with a depending arm 13 of the rock-shaft 9, which is journaled in suitable bearings and 70 which is provided with an upwardly-extending L-shaped arm 14, located adjacent to the headlight and connected with the same.

The double connection between the truck and the headlight causes the latter to follow 75 positively and automatically the movements of the front truck, so that the light is always thrown in the direction a locomotive is traveling and will illuminate a track in advance of a train on curves as well as a straight 80 track. The horizontal portion of the rock-shaft is supported by a bracket or brace 15; but any suitable bearings may be provided. The connections between the headlight and the truck may be arranged on the exterior of 85 the locomotive, as illustrated in Figs. 1 and 2 of the accompanying drawings, or they may extend through the smoke-box, as illustrated in Fig. 3.

The invention has the following advantages: The headlight by being positively connected with the truck follows the pivotal movements of the same and is automatically turned in the direction a locomotive is traveling when such direction is changed, and 95 the light is thrown upon the track when passing around curves as well as when traveling over a straight road. Also the particular connection between the headlight and the truck prevents the up-and-down movement 100 of the latter from being communicated to the headlight.

The salient feature of the invention resides in the connections between the headlight and

the front truck, and I desire it to be understood that changes in the form, proportion, and minor details of construction may be resorted to without departing from the spirit or 5 sacrificing any of the advantages of the invention.

What I claim is—

1. In a device of the class described, the combination with a locomotive or analogous 10 motor having a pivotally-mounted front truck, of a pivotally-mounted headlight arranged to swing laterally when the locomotive changes its direction, the substantially vertical lever fulcrumed between its ends and 15 adapted to oscillate, the lower end of the lever being connected to the truck, and means for connecting the upper end of the lever with the headlight, substantially as described.
2. In a device of the class described, the 20 combination with a locomotive, of a headlight pivotally mounted thereon, a rock-shaft journaled on the locomotive and provided with upwardly and downwardly extending arms, the upwardly-extending arm being connected

with the headlight, and a lever fulcrumed be- 25 tween its ends on the locomotive, connected at its upper end with the depending arm of the rock-shaft and having its lower end connected to the truck, substantially as de- scribed.

3. The combination with a locomotive, of a headlight pivotally mounted thereon, a horizontal rock-shaft journaled on the locomotive and provided with upwardly and downwardly extending arms, the upwardly-extending arm 35 being connected with and adapted to actuate the headlight, and means for connecting the downwardly-extending arm of the rock-shaft with the front truck of the locomotive, substantially as and for the purpose described. 40

In testimony that I claim the foregoing as my own I have hereto affixed my signature in the presence of two witnesses.

JAMES H. SLIGH.
